US0D1069916S

(12) **United States Design Patent** (10) **Patent No.:** **US D1,069,916 S**
(45) **Date of Patent:** **** Apr. 8, 2025**

(54) **GAMING MACHINE**

(71) Applicant: **SG Gaming, Inc.**, Las Vegas, NV (US)

(72) Inventors: **Robert C. Coon**, Chicago, IL (US);
Christian Kulujian, Chicago, IL (US)

(73) Assignee: **LNW Gaming, Inc.**, Las Vegas, NV
(US)

(**) Term: **15 Years**

(21) Appl. No.: **29/855,344**

(22) Filed: **Sep. 30, 2022**

(51) **LOC (15) Cl.** **21-03**

(52) **U.S. Cl.**

USPC **D21/369**

(58) **Field of Classification Search**

(57) **CLAIM**

The ornamental design for a gaming machine as shown and described.

DESCRIPTION

FIG. 1 is a front perspective view of a gaming machine showing my new design;

FIG. 2 is a front view thereof;

FIG. 3 is a left side view thereof;

FIG. 4 is a right side view thereof; and,

FIG. 5 is an enlarged view of the identified region of FIG. 1.

The broken line showing is included for the purpose of illustrating portions of the “article” and forms no part of the claimed design.

1 Claim, 5 Drawing Sheets
